MASONIC CONSISTORY RING

Arthur W. Lindholm, 659½ Wabash Ave.,
Terre Haute, Ind.

Filed May 9, 1961, Ser. No. 65,080

Term of patent 14 years

(Cl. D45—10)

FIGURE 1 is a top plan view of the masonic consistory ring of the present invention.

FIGURE 2 is a side elevational view thereof.

FIGURE 3 is an elevational view taken at right angles to the view shown in FIGURE 2.

FIGURE 4 is an elevational view looking at the opposite side from that shown in FIGURE 3.

FIGURE 5 is a bottom plan view thereof.

I claim:

The ornamental design for a masonic consistory ring, as shown.
